UNITED STATES PATENT OFFICE.

HAROLD DRABBLE, OF LONDON, AND DAVID WILLIAM EDGAR KYLE, OF CHISWICK,
LONDON, ENGLAND.

WINDSCREEN FOR VEHICLES.

Application filed February 4, 1924. Serial No. 690,612.

To all whom it may concern:

Be it known that we, HAROLD DRABBLE, a subject of the King of Great Britain and Ireland, residing at 88 Chancery Lane, 5 London, W. C., England, and DAVID WILLIAM EDGAR KYLE, a subject of the King of Great Britain and Ireland, residing at 31 Riverview Grove, Chiswick, London, W. 4, England, have invented new and useful 10 Improvements in and Relating to Windscreens for Vehicles, on which application has been made for Letters Patent in Great Britain, No. 26,951, filed 27th October, 1923, and No. 31,554, dated 15th December, 15 1923, of which the following is a specification.

The present invention relates to wind screens such as are used for the rear seats of motor vehicles.

20 An embodiment of the invention is illustrated by way of example in the accompanying drawings, in which—

Figure 1 shows a front view of the screen out of use.

25 Figure 2 shows a plan view of Figure 1 with the screen proper removed, and

Figure 3 shows a plan view of the device in use, with the screen proper removed.

30 Figure 4 shows an alternative form of the tension rod in two parts.

The device comprises a pair of horizontal arms 1, 2, pivoted vertically in suitable brackets 3, 4, secured to the body of the vehicle. The arms cross in plan and at 35 the crossing point a bracket 5 is secured to the arm 2 while the arm 1 slides through it. In this way the movements of the arms about their vertical pivots are definitely related. The lower arm 2 is fitted behind 40 the upper arm 1 which is cranked at 11 to allow the arms to go back into the position shown in Figure 2. To the arm 1 are secured two sockets 6, 7, while a socket 8 is 45 slidably mounted on the arm 2. This socket is provided with a clamping screw 9 so that it may be secured to the arm 2, which is flattened or grooved so that the socket does not rotate on the arm.

It will be understood that instead, the 50 arms might be of any other suitable section, and that the form of the brackets, sockets and clamping screw may be varied in any convenient manner. A tension rod 10 is pivoted to the socket 8 and to the socket

7 secured to the arm 1. In this way the 55 sliding movement of the bracket 8 is definitely related to the movement of the arms 1, 2, on their vertical pivots and if the bracket 8 is clamped, the whole framework 60 becomes fixed.

The screen proper 12 is hinged at its centre and is provided at the ends and centre with pins 13, 14, 15, adapted to fit respectively in the sockets 6, 7, 8. The screen is provided above the level of the supporting arms with windows 16 of celluloid or 65 similar transparent material and is continued below the form of a flexible apron 17, preferably of waterproof material.

In Figure 4 the tension rod 10 is in two 70 parts, the ends being overlapped and clamped by means of a sleeve and screw 111. This permits the distance between the sockets 7 and 8 to be adjusted to hold the screen properly stretched. The sockets 6, 75 7, 8, are at the same distance apart whatever the position of the frame, so that the screen is held stretched at the same tension at all times.

In use, the screen is mounted by the pins 80 13, 14, 15, in the sockets 6, 7, 8, the screw 9 loosened and the arms moved into the position shown in Figure 3, till the socket 7 butts hard against the bracket 5. The bracket 8 is then clamped by the screw 9, 85 the slight strain put on the framework during opening producing tension in the rod 10, thus holding the framework rigid.

When it is desired to leave the vehicle 90 the clamp screw 9 is loosened and the whole frame pushed back. By cranking the arm 1 at 11 the framework can be moved back until the arm ends have passed well beyond the back of the front seat and thus the doors of the vehicle can always be 95 completely cleared permitting the vehicle to be entered or left without obstruction. The amount by which the crank 11 projects from the back of the front seat is less than the depth of the upholstery and therefore 100 does not interfere with passengers in the front seat, as indicated by the dotted lines in Figure 2.

The screen proper may, if desired, be 105 lifted out and folded up and put away.

The screen can be readily adapted for vehicles of varying widths without overlapping the sides by suitably spacing the

brackets 3 and 4. Corresponding alteration must be made in the positions of the various sockets and brackets, adjustment of which will also permit the extent of opening to be varied.

What we claim is:—

1. A wind screen for the rear seats of motor and like vehicles, comprising a pair of crossed horizontal arms vertically pivoted to the vehicle body, a screen adapted to be supported by said arms, a rod having one end pivoted to one of said arms and the other slidably connected to the other of said arms, a stop on said last mentioned arm positioned to limit the sliding action of said rod so that it is held in tension when said arms are in the position of use and means for securing said arms in the position of use.
2. A wind screen for the rear seats of motor and like vehicles, comprising a pair of crossed horizontal arms vertically pivoted to the vehicle body, two sockets secured to one arm, a socket slidably mounted on the other arm, means for securing said sliding socket to its arm, and a screen hinged at its centre adapted to be mounted on said sockets.
3. A wind screen for the rear seats of motor and like vehicles, comprising a pair of crossed horizontal arms, vertical pivots on said arms, brackets on the vehicle body for said pivots, two sockets secured to one arm, a socket slidably mounted on the other arm, means for securing said sliding socket to its arm, and a screen hinged at its centre adapted to be mounted on said sockets.
4. A wind screen for the rear seats of motor and like vehicles, comprising a pair of crossed horizontal arms, vertical pivots on said arms, brackets on the vehicle body for said pivots, a bracket at the crossing point secured to one arm and sliding on the other, two sockets secured to one arm, a socket slidably mounted on the other arm, means for securing said sliding socket to its arm, and a screen hinged at its centre adapted to be mounted on said sockets.
5. A wind screen for the rear seats of motor and like vehicles, comprising a pair of crossed horizontal arms, vertical pivots on said arms, brackets on the vehicle body for said pivots, two sockets secured to one arm, a socket slidably mounted on the other arm, means for securing at a single operation both the first of said arms and the sliding socket, and a screen hinged at its centre adapted to be mounted on said sockets.
6. A wind screen for the rear seats of motor and like vehicles, comprising a pair of crossed horizontal arms, vertical pivots on said arms, brackets on the vehicle body for said pivots, two sockets secured to one arm, a socket slidably mounted on the other arm, means for securing said sliding socket to its arm, a tension bar pivoted to said sliding

socket and to one of said sockets on the first of said arms, and a screen hinged at its centre adapted to be mounted on said sockets.

7. A wind screen for the rear seats of motor and like vehicles, comprising a vertical pivot, an upper horizontal arm on said pivot cranked adjacent thereto, a lower horizontal arm, a vertical pivot thereon, a pair of brackets on the vehicle body in which said arms are mounted with the lower arm behind the cranked portion of the upper arm, two sockets secured to one arm, a socket slidably mounted on the other arm, means for securing said sliding socket to its arm, and a screen hinged at its centre adapted to be mounted on said sockets.

8. A wind screen for the rear seats of motor and like vehicles, comprising a pair of crossed horizontal arms, vertical pivots on said arms, brackets on the vehicle body for said pivots, a bracket at the crossing point secured to one arm and sliding on the other, two sockets secured to one arm, a socket slidably mounted on the other arm, means for securing said sliding socket to its arm, a tension bar pivoted to said sliding socket and to one of the sockets on the first of said arms, and a screen hinged at its centre adapted to be mounted on said sockets.

9. A wind screen for the rear seats of motor and like vehicles, comprising a vertical pivot, an upper horizontal arm on said pivot cranked adjacent thereto, a lower horizontal arm, a vertical pivot thereon, a pair of brackets on the vehicle body in which said arms are mounted with the lower arm behind the cranked portion of the upper arm, a bracket at the crossing point of said arms secured to one arm and sliding on the other, two sockets secured to one arm, a socket slidably mounted on the other arm, means for securing said sliding socket to its arm, and a screen hinged at its centre adapted to be mounted on said sockets.

10. A wind screen for the rear seats of motor and like vehicles, comprising a vertical pivot, an upper horizontal arm on said pivot cranked adjacent thereto, a lower horizontal arm, a vertical pivot thereon, a pair of brackets on the vehicle body in which said arms are mounted with the lower arm behind the cranked portion of the upper arm, two sockets secured to one arm, a socket slidably mounted on the other arm, means for securing said sliding socket to its arm, a tension bar pivoted to said sliding socket and to one of the sockets on the first of said arms, and a screen hinged at its centre adapted to be mounted on said sockets.

11. A wind screen for the rear seats of motor and like vehicles, comprising a vertical pivot, an upper horizontal arm on said pivot cranked adjacent thereto, a lower horizontal arm, a vertical pivot thereon, a pair of brackets on the vehicle body in which

said arms are mounted with the lower arm behind the cranked portion of the upper arm, a bracket at the crossing point of said arms secured to one arm and sliding on the other, two sockets secured to one arm, a socket slidably mounted on the other arm, means for securing said sliding socket to its arm, a tension bar pivoted to said sliding socket and to one of the sockets in the first 10 of said arms, and a screen hinged at its centre adapted to be mounted on said sockets.

12. A wind screen for the rear seats of motor and like vehicles, comprising a vertical pivot, an upper horizontal arm on said pivot cranked adjacent thereto, a lower horizontal arm, a vertical pivot thereon, a pair of brackets on the vehicle body in which said arms are mounted with the lower arm behind the cranked portion of the upper arm, a bracket at the crossing point of said arms secured to one arm and sliding on the other, two sockets adjustably secured to one arm, a socket slidably mounted on the other arm, means for securing said sliding socket to its 25 arm, an adjustable tension bar pivoted to said sliding socket and the socket on the other arm nearer its vertical pivot, and a

screen hinged at its centre adapted to be mounted on said sockets.

13. A wind screen for the rear seats of 30 motor and like vehicles, comprising a vertical pivot, an upper horizontal arm on said pivot cranked adjacent thereto, a lower horizontal arm, a vertical pivot thereon, a pair of brackets on the vehicle body in which 35 said arms are mounted with the lower arm behind the cranked portion of the upper arm, a bracket at the crossing point of said arms secured to one arm and sliding on the other, two sockets adjustably secured to one 40 arm, a socket slidably mounted on the other arm, a hand screw for securing said sliding socket to its arm, an adjustable tension bar in two parts having overlapping ends pivoted to said sliding socket and to the socket 45 on the other arm nearer its vertical pivot, a sleeve and screw securing said overlapping ends, a screen hinged at its centre, and pins on said screen adapted to enter said sockets.

In testimony whereof we have signed our 50 names to this specification.

HAROLD DRABBLE.

DAVID WILLIAM EDGAR KYLE.
